US00D941174S

(12) **United States Design Patent** (10) Patent No.: **US D941,174 S**
(45) Date of Patent: **** Jan. 18, 2022**

(54) **SMOKE AND CARBON MONOXIDE SENSOR**

(71) Applicant: **AMAZON TECHNOLOGIES, INC.**,
Seattle, WA (US)

(72) Inventors: **Mark Siminoff**, Mountain View, CA
(US); **Timothy G. Wellener**,
Phoenixville, PA (US); **Vinay Sao**,
Malvern, PA (US); **Peter Gerstberger**,
Laguna Niguel, CA (US); **Andrew L.
Russell**, Philadelphia, PA (US);
Christopher Loew, Palo Alto, CA (US)

(73) Assignee: **Amazon Technologies, Inc.**, Seattle,
WA (US)

(***) Term: **15 Years**

(21) Appl. No.: **29/696,893**

(22) Filed: **Jul. 2, 2019**

Related U.S. Application Data

(63) Continuation of application No. 29/623,306, filed on
Oct. 24, 2017, now Pat. No. Des. 860,026.

(57) **CLAIM**

The ornamental design for a smoke and carbon monoxide sensor, as shown and described.

DESCRIPTION

FIG. 1 is a front perspective view of a smoke and carbon monoxide sensor according to the present design;

FIG. 2 is a front elevational view of the smoke and carbon monoxide sensor of FIG. 1;

FIG. 3 is a rear elevational view of the smoke and carbon monoxide sensor of FIG. 1;

FIG. 4 is a right-side elevational view of the smoke and carbon monoxide sensor of FIG. 1;

FIG. 5 is a left-side elevational view of the smoke and carbon monoxide sensor of FIG. 1;

FIG. 6 is a top plan view of the smoke and carbon monoxide sensor of FIG. 1; and,

FIG. 7 is a bottom plan view of the smoke and carbon monoxide sensor of FIG. 1.

In the drawings, the broken lines depict portions of the smoke and carbon monoxide sensor that form no part of the claimed design.
